MILK CARTON OR THE LIKE

Albert B. Mojonnier, 5357 N. East River Road,
Chicago, Ill.

Filed Aug. 14, 1961, Ser. No. 66,346

Term of patent 14 years

(Cl. D58—12)

Fig. 3

Fig. 4

FIG. 1 is a perspective view of a milk carton or the like, showing my new design;

FIG. 2 is a side elevational view of the same, looking at a narrow side thereof;

FIG. 3 is a top plan view of the same; and

FIG. 4 is a side elevational view of the same, looking at a longer side thereof.

The dominant features of my design reside in the portions shown in full lines.

I claim:

The ornamental design for a milk carton or the like, substantially as shown and described.
